UNITED STATES PATENT OFFICE.

JONATHAN FRANK CHILD, OF MARLBOROUGH, MASSACHUSETTS.

SHOE-FINISHING JACK.

SPECIFICATION forming part of Letters Patent No. 317,091, dated May 5, 1885.

Application filed March 5, 1885. (No model.)

To all whom it may concern:

Be it known that I, JONATHAN FRANK CHILD, of Marlborough, in the county of Middlesex and Commonwealth of Massachusetts, 5 have invented certain new and useful Improvements in Shoe-Finishing Jacks; and I do hereby declare that the following is a full, clear, and exact description of the same, reference being had to the accompanying drawings, forming 10 a part of this specification, in which—

Figure 1 represents a top or plan view of a shoe-finishing jack embracing my said improvements, the drawings being one-half full size. Fig. 2 represents a side view of the 15 parts shown in Fig. 1, looking in the direction of arrow 1; and Fig. 3 represents a central vertical section on line A B, Fig. 1, looking in the direction of arrow 1.

To enable those skilled in the art to which 20 my invention belongs to make and use the same, I will proceed to describe it more in detail.

The object of my present invention is to produce a shoe-finishing jack adapted for use 25 upon any work that is required to be done on a shoe after the last is taken out or removed from it, and which improved jack, with but slight and simple adjustments, can be used with all sizes of shoes, from and including 30 children's shoes to and including men's large brogans.

In the drawings, the part marked C represents a section of the bench having an opening, C', cut out to receive the duplicate coils 35 a a of spring D, operating treadle cord or chain E, and guide-stem or projection E' of the adjustable jack-stand F, the latter being held upon the jack-base G by means of lugs G', which are fastened to its under side and 40 project under the inwardly-projecting flange b of the base G, which latter is securely fastened to the top of the bench C. With this arrangement the jack-stand F can be turned round and afterward fixed in any desired position by means of the lug c on the end of thumb-screw d, as fully indicated in Figs. 2 and 3 of the drawings. From the upper side of the jack-stand F rises a projection, F', the upper end of which is cored or bored out to 45 receive the stem H of the standard H' of the

last part I, the part I being cored out on its under side, as seen at I', with an opening, e, in the rear part, as fully indicated in Figs. 2 and 3 of the drawings.

Upon the rear end of the adjustable jack-stand F are cast or otherwise secured two flanged guide-pieces, f f, between which is held the sliding heel part J, said part J being provided with projecting flanges to slide underneath the flange parts of the guide-pieces 60 f, as fully indicated in dotted lines, Fig. 1, and full lines, Fig. 3.

In the upper inner face of the heel part J is formed a slot, in which is hinged or pivoted the heel end of the shank-supporting piece J. 65

A double spring, B, is secured between the front stationary part, H, and the adjustable part J, as follows: The loop part h of said spring rests or bears against the inner face of the movable part J, a pin, h', passing through 70 the loop into the adjustable part J, while the ends of the double spring are bent and entered into holes formed in the inner side of the stationary projection F'. By this arrangement an open space is left between the loop 75 of spring D and the arms g thereof, and through this opening the chain or treadle-cord E passes, the upper end being fastened in any convenient and proper manner to the adjustable jack part J, and then passing between the loop and ends g of spring D over a pulley, E'', pivoted in a slot formed in the lower part of the upwardly-projecting piece F', thence down through the guide-piece E' and opening C', and connected to a foot-treadle, 80 K, said treadle being arranged and secured to the lower end of the operating cord or chain E in any suitable manner. In the drawings the operating-cord is shown secured to the treadle in the same manner as the upper end 85 by means of a screw, while it has a swivel-link, L, for the purpose of permitting the jack to be turned on the base-piece G into any desired position without twisting or cramping the operating cord and treadle. 90

Instead of the treadle-cord being fastened, as indicated in the drawings, it may be drawn through and bent up against the treadle and a screw passed through it or fastened in any other convenient manner. 95

To prevent the heel part of the jack from slipping out, a stop-screw, M, is secured to the adjustable jack-stand F, and the base of the heel part J is slotted out to allow it to slide out, as indicated in full lines, Fig. 1. The part which supports the front of a shoe and which is made in the form of a last can be removed with its standard H' and stem H, and another (smaller or larger) last part I substituted therefor, thus enabling this part of the jack to be adjusted quickly for supporting the front part of different sizes of shoes.

The heel part N of the jack part J is also made so that it can readily be removed and a larger or smaller piece substituted for the purpose of supporting the heels of different-sized shoes. This is accomplished by cutting away a portion of the upper rear part of J and applying a piece, N, having a pin, N', which passes down into a hole in the upper end of jack part J. For instance, if it is desired to apply a heel part which projects farther back, the one shown in full lines, Fig. 3, is removed and another inserted in its place extending back, as indicated in dotted lines, same figure.

If desired, a spring-plate and pin may be applied to one side of the projection F' for holding the stem H from being pulled out while the jack is in use. This spring-plate can be easily sprung back, thereby withdrawing its pin from the holes in the part F' and stem H, thereby permitting the stem to be withdrawn and another with a different-sized last part I inserted in lieu thereof.

From the base-piece G projects an arm, O, to which is pivoted the piece P, which in turn is secured in any proper manner to the top of the bench, and by which arrangement the jack can be swung over to one side for the purpose of finishing the edge of the shoe, and as the jack-stand F can be turned round the shoe can be turned, so that without changing the position of the piece P each edge of the shoe can be alternately turned up and exposed to the view of the operator for finishing, thus rendering the device very convenient in this respect, and, if preferred, in any case the part P can be quickly removed from the bench and fastened to it in any other position less than an entire revolution of the base-piece G.

In Fig. 1 of the drawings is shown in dotted lines one position in which the parts F, I, J, and N may be turned when necessary for convenience in finishing a shoe.

The parts shown in full lines in the drawings represent such an arrangement of parts as will enable the jack to be used in finishing shoes of the sizes six to eleven, inclusive, and by taking off the last part I and substituting one corresponding to the front part of the last for a boy's shoe, the device will be adapted to finishing numbers one to five, including women's shoes, and by substituting a youth's size last part I, the device can be used on all children's shoes. Then, again, by substituting in

lieu of the part N, a heel part of the size indicated by dotted lines in Figs. 2 and 3, the device as thus shown in the drawings is adapted for use in finishing sizes eleven to thirteen, inclusive, men's brogans.

One great advantage of my present improvement consists in the perfect form in which the shoe is retained while being finished.

After the last is removed from the shoe the heel part J is forced up toward the part I and the shoe placed upon the last part I and over the heel part N, when the part J is allowed to move back by the action of spring D, thereby causing the shoe to be held in an easy and perfect manner during the operation of finishing, the action being so easy and perfect as not to remove or injure the crimping of the shoe, but to leave it just as perfect in this respect as when it comes off the last.

My jack is also adapted for use in performing all light stamping required to be done on a shoe, and that, too, without any fear of breaking it.

The operator in removing a shoe from the jack has only to place his foot upon the treadle K and give a slight pressure, when the jack part J will be drawn forward, as indicated in dotted lines, Fig. 3, thereby relieving the part N from pressure against the heel part of the shoe, which can then be readily slipped off and another placed thereon, after which, the foot being removed from the treadle, spring D causes the movable part J to move back into its normal position, thereby holding the shoe in an easy but secure position for finishing.

Owing to the manner of holding the base of part J under the flange-pieces f' f' of the flanged pieces f f, the friction is such that the force exerted upon the upper part of the jack-piece J in finishing the shoe is not sufficient to move the part J out of position. When the movable part J of the jack is moved forward, the point m of the hinged shank-supporting piece J' will run up on the inclined face n of the part H', and, passing through the opening e, will run into the opening in the last part I.

Those skilled in the art to which my invention belongs will readily understand and appreciate the great practical advantages due to its use.

Having described my improvements in shoe-finishing jacks, what I claim therein as new and of my invention, and desire to secure by Letters Patent, is—

1. The combination, with base F, for supporting the jack, of the base-piece G, provided with flange b, lugs G', thumb-screw d, and lug c, substantially as and for the purpose set forth.

2. The combination, with the base-pieces F and G, provided with an opening for the reception of spring D, of the guide-piece E' and operating-cord E, substantially as and for the purposes set forth.

3. The combination, with the movable part J, of the spring D, provided with duplicate coils a, substantially as and for the purpose set forth.
5. The combination, with the stationary part H' and movable part J, of the jack-spring D and operating cord or chain E, connected with treadle K, substantially as and for the purpose set forth.
5. The combination, in a jack for finishing 10 shoes, of the stationary part I, movable part J, spring D, and hinged shank-support J', substantially as and for the purpose set forth.

JONATHAN FRANK CHILD.
